UNITED STATES PATENT OFFICE

2,655,825

AUTOMATIC SHEET METAL REFORMING
HAMMER

Joseph Gendron, Hollywood, Fla.

Application November 29, 1951, Serial No. 258,959

1 Claim. (Cl. 81—15)

1

The present invention relates to new and useful improvements in tools for removing dents from sheet metal and more particularly to a power operated picking hammer for use with automobile body and fender repair work.

An important object of the invention is to provide a tool of this character adapted for use in places normally inaccessible to hand operated tools and wherein the hammer is rapidly actuated to quickly complete the job.

Another object is to provide a device of this character of simple and practical construction, which is efficient and reliable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view;

Figure 2 is a longitudinal sectional view; and,

Figure 3 is an enlarged transverse sectional view taken on a line 3—3 of Figure 2.

Referring now to the drawing in detail, wherein for the purpose of illustration I have disclosed a preferred embodiment of my invention, the numeral 5 designates a barrel in the center of which a hollow plunger 6 is slidable. A rod 7 is welded or otherwise suitably fixed at its central portion to plunger 6 with front and rear guide plugs 8 and 9 pressed in or otherwise suitably fixed in the front and rear ends respectively of the barrel. Front and rear opposing coil springs 10 and 11 are positioned in the barrel, front spring 10 being held between the plunger 6 and front fixed plug 8 and rear spring 11 being held between plunger 6 and rear fixed plug 9. The rod 7 extends through rear plug 9 to project rearwardly beyond the rear end of the barrel into the front end of a pulsating type pneumatic tool 12 of a conventional type for actuation by the reciprocating piston 13 of the tool. The tool 12 is attached to the rear end of barrel 5.

A head 14 is constructed of a pair of spaced apart side plates 15 and 16 with a rear collar 17 welded between the rear edges of the plates and is threaded on the front end of the barrel. A front collar 18 is welded between the front edges of the plates substantially at right angles to rear collar 17.

A hollow guide plug 19 is threaded in the lower end of front collar 18 and in which the front end of a reciprocable pick hammer 20 is slidable. The

2

hammer is held in a retracted position by a coil spring 21 held between plug 19 and a flange 22 adjacent the rear end of the hammer. The rear end 23 of the hammer is received in a recess 24 at the front end of a substantially bell crank arm 25 which is pivoted adjacent its central portion on a transverse pin 26 supported by the plates 15 and 16 and with the rear end 27 of the bell crank arm positioned in the path of forward movement of the front end of rod 7.

In the operation of the device rod 7 is pushed forwardly by the piston 13 of the pneumatic tool causing the front end of the rod to strike the rear end of bell crank arm 25 to rock the arm and project hammer 20. During forward movement of rod 7 the plunger 6 carried by the rod compresses front spring 10 and upon completion of the forward stroke of the rod spring 10 returns the rod rearwardly and spring 21 retracts hammer 20 and such action of both springs 10 and 21 is opposed by rear spring 11 which is compressed by the rearward movement of plunger 6 and tends to check the return movement of the rod and also tends to hold the rod engaged with arm 25 and results in a rapid reciprocative movement of the rod.

Accordingly, by placing the front end of the hammer against a dent in a fender or other sheet metal work the dent will be rapidly hammered to smooth the same.

Although the barrel 5 is shown attached to a pneumatically operated tool it will be apparent that the same may also be used with electrically or mechanically operated tools as well.

In view of the foregoing description taken in conjunction with the accompanying drawing it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and the scope of the appended claim.

Having thus described the invention, what is claimed as new is:

A sheet metal picking hammer comprising a barrel, a reciprocable rod in the barrel, a head at the front end of the barrel, a guide in the head, an elongated hammer slidably mounted in the guide and positioned substantially at right angles to the rod, spring means retracting the hammer, a substantially bell-crank arm pivoted to the head and having one end engaging the rear

end of the hammer and having its other end in the path of movement of the rod, front and rear springs in the barrel, an abutment at the front end of the barrel for the front spring, an abutment at the rear end of the barrel for the rear spring, means fixed to the rod for movement therewith and separating said front and rear springs to compress the front spring upon a forward movement of the rod and to compress the rear spring upon a rearward movement of the rod, said front and rear springs opposing each other to tend to reciprocate the rod, and said rear spring maintaining the forward end of the rod.

in engagement with said bell-crank arm, and means connected to the rear end of the rod to actuate the same.

JOSEPH GENDRON.
